UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 7, 1922. Serial No. 592,929.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

The present invention relates to typewriting machines, and more particularly to means for returning the carriage and releasing the feed-devices.

An object of the invention is to expedite the replacing of typed work-sheets with work-sheets to be typed, more particularly bills and other printed forms which require the typing thereon of but a single line, or a few lines, at the most, and which, therefore, necessitate the frequent releasing of the feed-devices, for quickly withdrawing a typed bill or work-sheet, and for quickly replacing it with a bill or work-sheet to be typed.

Another object of the invention is to enable the concomitant return of the carriage and release of the feed-devices by the use of the left hand, while at the same time the left hand introduces an untyped bill or other work-sheet, and the right hand withdraws the bill or other work-sheet just typed.

Another object of the invention is to produce a feed-device-releasing and carriage-returning mechanism which may be readily installed upon a usual typewriting machine, particularly upon the standard Underwood typewriting machine, merely by the addition and replacement of a few parts.

According to the present invention, mechanism is provided for concomitantly returning the carriage and releasing the feed-devices, which may be the usual feed-rolls, from the platen, such mechanism including a single finger-piece, actuatable by the left hand of the typist, while the bill or work-sheet to be typed is at the same time inserted in the machine. More particularly, a feed-roll-releasing rock-shaft extends along the top of the platen, parallel therewith, and carries said finger-piece adjacent and beyond the left side of sheet-guiding means at the introductory side of the platen, and said sheet-guiding means may be a guide-chute of less width than the length of the platen,

Other features and advantages will hereinafter appear.

In the accompanying drawings,

Figure 1 is a front elevation of the usual Underwood platen-frame equipped with the mechanism of the present invention.

Figure 2 is a vertical section, substantially on the line 2—2 of Figure 1, as viewed from the right, and further shows parts of the carriage and of the main frame of the machine, also the manner of operating the mechanism of the present invention while inserting in the machine a sheet to be typed.

In the illustrated embodiment of the present invention, as applied to a standard Underwood typewriting machine, there is provided a finger-piece comprising a laterally horizontally-extending depressible part 1 to be depressed by any one or all of the three fingers of the left hand to cast off or release the usual spring-pressed front and rear feed-rolls 2 and 3 which run upon the lower side of the platen 4. At its right end the depressible finger-piece part 1 carries an upstanding curved part 5 to be engaged by the middle finger of the left hand to return the carriage 6 towards the right for the beginning of a new line. The depressible finger-piece part 1 is carried by a pair of rearwardly and slightly upwardly-projecting finger-piece arms 7 fixed upon the left end portion of a rock-shaft 8 which extends above the platen 4 parallel therewith and slightly to the rear of the platen-axle 9. The rock-shaft 8 is journaled at its right end in a small bracket 10, outwardly from the right-hand end of the platen 4, and at its left end is journaled in a similar bracket 11, inwardly from the left-hand end of the platen 4, the upstanding brackets 10 and 11 being carried by a transverse bar 12 detachably secured at its ends upon the tops of the right and left end walls or end pieces 13 and 14, respectively, of the platen-frame and in which the platen-axle 9 is journaled.

When the finger-piece part 1 is depressed, it will rock shaft 8 in a clockwise direction, as seen in Figure 2 and as viewed from the right in Figure 1, to lift a forwardly-projecting lever-arm 15 fixed upon the right end of the rock-shaft 8, to draw upwardly a depending link 16 pivoted to the forward end of the lever-arm 15, the link 16 at its lower end being pivotally connected by a pivot,

100
105

pin 17 to the upper end of a link 18, which forms a part of the usual cast-off mechanism for the feed-rolls 2. The remainder of the usual cast-off device for the feed-rolls 2 and 3, actuatable by depressing the finger-piece part 1, comprises a normally forwardly and downwardly-extending lever-arm 19, to which the lower end of the lower link 18 is pivotally connected, and which is fixed upon the right-hand end of a cam-shaft 20 journaled in bearings 21 depending from a tie-rod 22 connecting the platen-frame ends 13 and 14 beneath the platen 4. Rocking of the cam-shaft 20 operates, by means of cam-forming flats 23 thereon, to separate downwardly-extending arms 24 and 25, which are respectively connected to, and form bell-cranks with, forwardly-projecting arms 26 carrying the front feed-rolls 2, and rearwardly-projecting arms 27 carrying the rear feed-rolls 3, said bell-cranks being pivoted upon the platen-frame tie-rod 22.

For simplicity of construction and also for use if found convenient, the usual feed-roll release lever 28, terminating in a finger-piece 29, is retained, being fixed upon the outer end of a short shaft 30 journaled in the right-hand platen-frame end 13. Upon the inner end of the shaft 30 is fixed a feed-roll releasing lever-arm 31 pivoted at 17 to the upper end of the lower link 18 coincidentally with the pivotal connection of the upper link 16 thereto. However, it is within the province of the invention to omit the usual feed-roll cast-off lever 28, in which case the upper link 16 may be extended downwardly and connected directly to the cam-shaft arm 19.

Pressure of the middle finger of the left hand against the upstanding finger-piece part 5, which may take place concomitantly with the depression of the depressible finger-piece part 1 to release the feed-rolls, will return the carriage 6, on which the platen-frame is mounted, towards the right, the carriage 6 being mounted for letter-feed and return movements upon a rear rail 33 and a front rail 34, upon the latter of which runs a roller 35 on the carriage, the rear and front rails 33 and 34 being on a main frame 36. The operations of casting off or releasing the feed-rolls 2 and 3 by depressing the finger-piece part 1, and of returning the carriage 6 by moving the upstanding finger-piece part 5 towards the right, may take place concomitantly.

In the particular class of work to be done with the typewriting machine embodying the present invention, the bills or work-sheets are commonly comparatively narrow and of less width than the length of the platen. For effectively directing or guiding such narrow bills or work-sheets to the platen, the usual rear paper-table, not shown,

may be removed from the machine and replaced at the introductory side of the platen by a guide-chute 37, comprising a floor portion 38 and upstanding side walls 39, which encircle the platen at 40, so as to be slipped thereover, the floor 38 of the guide-chute being extended beneath the platen to form a curved paper-apron 41, which is cut away in the usual manner to accommodate the feed-rolls 2 and 3. At the rear of the platen, the guide-chute 37 is supported by a usual transverse rear bar 42 forming a part of the platen-frame. The guide-chute 37 is preferably located, as shown in Figure 1, at the right-hand end portion of the platen, and is shown as properly positioned to co-operate with two of the front-rolls 2, and corresponding with two of the rear feed-rolls 3, the front and rear feed-rolls 2 and 3 at the left not being used.

The finger-piece, having the depressible part 1 for releasing the feed-rolls 2 and 3 and the upstanding part 5 for returning the carriage, is located above the left-hand portion of the platen 4, beyond and adjacent the left side of the guide-chute 37, the upstanding part 5 of the finger-piece being at the left and at the front of the upper or forward edge of the left-hand side wall 39 of the guide-chute, so that, while three fingers of the left-hand may actuate the finger-piece, as hereinbefore described, for concomitantly releasing the feed-rolls 2 and 3 and returning the carriage 6, the thumb and index finger of the left hand may grasp a bill or work-sheet 43 for introducing it into the machine downwardly at the introductory side of the platen over the floor portion 38 of the guide-chute and between the platen 4 and the paper-apron 41 forming a part of the guide-chute 37. The bill or other work-sheet 43 may be thus inserted concomitantly, or substantially concomitantly, with the release of the feed-rolls and return of the carriage.

Springs 44 and 45 engage the respective front and rear feed-roll carrying arms 26 and 27 to press the bill or work-sheet against the lower side of the platen, and for returning the feed-rolls to their feeding positions when left free to do so. The upward or return movement of the finger-piece, having the depressible part 1 is, of course, limited by the cam-flats 23 on the cam-shaft 20 when the feed-rolls are returned by their springs 44 and 45 to their feeding positions; and the downward or feed-roll-releasing movement of said finger-piece is limited by reason of a small spacing washer 46 on the pivot-pin 17 (which latter connects together the upper and lower links 16 and 18 and the lever-arm 31 of the usual cast-off lever 28) abutting against the lower side of a stop 47 formed on the right-hand platen-frame end-plate 13. Figure 1.

The carriage 6 may be drawn along in letter-feed direction by means of a usual spring-barrel, not shown, under the control of suitable escapement mechanism, not shown, but which may be the same as in the standard Underwood machine. In case it is desired to write more than one line, the platen may be line-spaced either by means of the usual handle knobs 48 on the ends of the platen-axle 9, one of these knobs or finger-wheels being shown at the left in Figure 1, or the platen may be line-spaced and the carriage returned by means of the usual or any suitable line-spacing and carriage-returning mechanism, of which only a line-space ratchet-wheel 49 is shown in Figure 1. The making out of telephone bills is a good example of the class of work which the machine of the present invention is intended to do, and it is also adapted for use to make out other similar small bills which require the typing of only a single line, or in some cases, only a few lines.

While the invention has been described in connection with the insertion of the fresh bills by the left hand, it can also be used to advantage by using the left hand to remove the finished bills and the right hand to insert the fresh ones. In this case, the operator returns the carriage and casts off the feed-rolls with the left hand, then reaches for the finished bill with the left hand. In the meantime, he has picked up a fresh bill with the right hand and inserts and adjusts it while the left hand is placing the finished bill at one side of the machine. Should the operator succeed in adjusting the new bill with his right hand before the left hand can return to assist in this operation, he will restore the feed-rolls by actuating the finger-piece 29 with the right hand; otherwise, he will restore the feed-rolls by actuating the finger-piece 1 with his left hand.

Variations may be resorted to within the scope of the invention, and portions of the improvements may be used without others.

Having thus described my invention, I claim:

1. In a typewriting machine, the combination with a platen, a carriage therefor movable in letter-feed and return directions, and a pressure device for holding work-sheets to the platen, of a carriage-returning handle located above the platen for convenient operation by the left hand, controlling connections from said handle to the pressure device, and a horizontally disposed finger-piece on the handle positioned to be engaged and depressed by fingers of the left hand to release said pressure device at the time when the same fingers are moving the handle to the right to return the carriage.

2. In a typewriting machine, the combination with a revoluble platen and feed-

rolls for holding a work-piece thereagainst, of a carriage for the platen, a work-guiding chute on the carriage, a carriage-returning handle directly above the platen and adjacent said chute, and operating connections between said handle and the feed-rolls for releasing the latter at the same time that said handle is moved to the right to return the carriage.

3. In a typewriting machine, in combination, a platen, a carriage for the platen movable in letter-feed and return directions, a chute on the carriage at the introductory side of the platen of less width than the length of the platen for guiding narrow work-sheets to the platen, a feed-roll to co-operate with the platen, and means for releasing the feed-roll including a finger-piece adjacent the left side of said chute to be actuated by the left hand for concomitantly releasing the feed-roll and returning the carriage while the fingers of the same hand may grasp a work-sheet in position to be inserted downwardly between said chute and platen.

4. In a typewriting machine, in combination, a platen, a carriage for the platen movable in letter-feed and return directions, a chute on the carriage of less width than the length of the platen and at the introductory side of the right end portion of the platen, a feed-roll for the platen in alignment with said chute, and releasing means for the feed-roll including a finger-piece above the platen and adjacent the left side of said chute to be actuated by the left hand for concomitantly releasing the feed-roll and returning the platen while the fingers of the same hand may grasp a work-sheet in position to be inserted downwardly between said chute and platen.

5. In a typewriting machine, in combination, a platen, a carriage therefor movable in letter-feed and return directions, sheet-guiding means at the introductory side of the platen, a feed-roll to co-operate with the platen, and means for releasing the feed-roll including a handle mounted directly above the platen adjacent said sheet-guiding means, and operating connections passing from said handle around one end of the platen to the feed-roll.

6. In a typewriting machine, in combination, a platen, a carriage therefor movable in letter-feed and return directions, a guide-chute at the introductory side of the platen of less width than the length of the platen, a feed-roll to run upon the lower side of the platen, and means for releasing the feed-roll including a finger-piece mounted directly above the platen adjacent the left side of said chute to have a rocking movement to release the feed-roll and to travel with the carriage for returning the latter and operating connections passing around the

right end of the platen from the finger-piece to the feed-roll.

7. In a typewriting machine, in combination, a platen, a carriage therefor movable in letter-feed and return directions, a feed-roll for holding a work-piece against the platen, and means for releasing the feed-roll and for concomitantly returning the carriage including a rock-shaft extending 10 along the top of the platen parallel therewith to travel with the carriage, and operating means directly above the platen fixed upon the rock-shaft, comprising a finger-piece depressible by the extended fingers of the hand for actuating the rock-shaft to release the feed-roll, and a second finger-piece associated with said first-named finger-piece and engageable by a side movement of the fingers of said hand 20 whereby to return the carriage.

8. In a typewriting machine, in combination, a platen, a carriage therefor movable in letter-feed and return directions, sheet-guiding means at the introductory side of the 25 platen, a feed-roll to co-operate with the platen, and means for releasing the feed roll and for concomitantly returning the carriage comprising a rockable finger-piece mounted directly above the platen adjacent 30 to the front of said sheet-guiding means to travel with the carriage, said finger-piece having a depressible part by which it may be rocked to release or apply the feed-roll and having an upstanding part by which 35 it may be moved together with the carriage for returning the carriage.

9. In a typewriting machine, in combination, a platen, a carriage therefor movable in letter-feed and return directions, sheet-side-guiding means at the introductory side 40 of the platen, a feed-roll to co-operate with the platen, and means for releasing the feed-roll and for concomitantly returning the carriage comprising a finger-piece above 45 the platen and adjacent the left side of said sheet-side-guiding means mounted to rock upon an axis parallel with the platen and to travel with the carriage, said finger-piece having a horizontally-extending 50 depressible part engageable by fingers of the left hand for rocking the finger-piece to release the feed-roll and having an upstanding part engageable at the same time by one of said fingers for moving the finger-piece 55 together with the carriage for returning the carriage.

10. In a typewriting machine, in combination, a platen, a carriage for the platen movable in letter-feed and return directions, 60 a spring-pressed feed-roll to run upon the lower side of the platen, a rock-shaft journaled on the carriage and extending along the top of the platen parallel therewith to one end thereof, means connected to the end 65 of the rock-shaft adjacent the end of the

platen for releasing the feed-roll upon rocking of the rock-shaft, and a finger-piece carried by the rock-shaft intermediate the ends of the platen for rocking the rock-shaft to release the feed-roll and for moving the 70 rock-shaft endwise together with the platen and carriage for returning the carriage.

11. In a typewriting machine, in combination, a platen, a carriage for the platen movable in letter-feed and return directions, 75 a spring-pressed feed-roll to run upon the lower side of the platen, a rock-shaft journaled on the carriage and extending along the top of the platen parallel therewith to one end thereof, means connected to the end 80 of the rock-shaft adjacent the end of the platen for releasing the feed-roll upon rocking of the rock-shaft, a finger-piece carried by the rock-shaft intermediate the ends of the platen for rocking the rock-shaft to release the feed-roll and for moving the rock-shaft endwise together with the platen and carriage for returning the carriage, and a guide chute on the carriage at the introductory 85 side of the platen of less width than the length of the platen, said finger-piece being located adjacent the left side of said chute to be actuated by the left hand while the same hand may grasp a work-sheet in position to be inserted in said chute downwardly 90 and around the platen at the introductory side thereof.

12. In a typewriting machine, in combination, a platen, a carriage for the platen movable in letter-feed and return directions, 100 sheet-guiding means on the carriage at the introductory side of the platen, spring-pressed feed-rolls to run upon the lower side of the platen, a rockable cam-shaft for releasing the feed-rolls, a rock-shaft journaled 105 on the carriage to travel with the carriage and extending above the platen, parallel therewith, to the right-hand end of the carriage and connected at its right-hand end to said cam-shaft, for releasing the feed-rolls 110 when the rock-shaft is rocked, and a finger-piece carried by the left-hand end portion of said rock-shaft beyond the left side of said sheet-guiding means, and having a depressible part for rocking the rock-shaft to 115 release the feed-rolls, and having an upstanding part connected to said depressible part at the right thereof for returning the carriage.

13. In a typewriting machine, a platen, a carriage therefor, a releasable pressure device for holding a work-piece against the platen, a carriage-returning handle disposed above the platen intermediate the ends thereof, operating connections between the pressure device and the handle, the latter depressible for actuating said connections to release the pressure device at the same time that said handle is moved to the right to return the carriage. 120 125 130

14. In a typewriting machine, a platen, a carriage therefor, a releasable pressure device for holding a work-piece against the platen, work-guiding means at the right end portion of the platen, a carriage-returning handle disposed adjacent said guiding means, connections between the pressure device and the handle, the latter being operable for actuating said connections to release and hold released said pressure device during return movement of the carriage.
15. In a typewriting machine, a platen, a carriage therefor, a releasable pressure device for holding a work-piece against the platen, a carriage-returning handle, connections between the pressure device and the handle, the latter operable for actuating said
- connections to release or restore said pressure device, and an auxiliary finger-piece operatively connected to the pressure device whereby to control said device independently of the carriage-returning handle.
16. In a typewriting machine, a platen, a carriage therefor, a releasable pressure device for holding a work-piece against the platen, a carriage-returning handle, connections between the pressure device and the handle, the latter operable for actuating said connections to release or restore said pressure device, and an auxiliary finger-piece arranged to operate said connections to control the pressure device independently of the carriage-returning handle.

JESSE A. B. SMITH.
